MEANS AND METHOD OF DETERMINING
THE INCLINATION OF WELL HOLES

Carl A. Reinhard, Los Angeles, Calif.

Application August 28, 1929, Serial No. 388,944

20 Claims. (Cl. 33—205.6)

This invention relates to devices and methods employed in well drilling and particularly to devices and methods for ascertaining whether the bottom of a well hole is inclined or not. The 5 invention concerns a device adapted to be dropped into a well carrying an acid bottle forming an indicating mechanism for indicating and recording the inclination of the device when it comes to rest near the bottom of the well hole. 10 As devices which are freely dropped in wells for various purposes, such as detonating nitro-glycerine, are referred to in the art as go-devils, I refer to my device as an acid bottle go-devil. It is an object of this invention to provide 15 an acid bottle go-devil having a flexible body adapted to be dropped through a drill pipe into a well. The flexibility of the body enables one end of it to be moved laterally with respect to the other and the flexible connection between the ends of the body forms a cushion.

Prior to the development of my invention a customary method of determining whether or not a well that was being drilled by means of a rotary well drilling apparatus had deviated 20 from the vertical was to withdraw the drill pipe from the hole, mount an acid bottle on a bailer, and lower the bailer into the well by means of a sand line. The bottle, which contained an etching acid, was thus lowered into the well and 25 allowed to remain at rest therein a sufficient time to allow the acid to eat the walls of the bottle up to the level of its surface. This procedure was awkward, cumbersome, and dangerous. Time was consumed in rigging up to lower 30 the bailer by means of the sand line and, in addition, there was always a danger of the bailer becoming caught or hung in the open hole of the well, that is, that portion of the well which may be below previously set casing. The uncased 35 walls of the well were subject to caving around the sand line and over the bailer, resulting in its becoming hung and unrecoverable. Also, in such instances where the mud or circulation fluid in the well tend to settle there was danger of the bailer becoming lost in the well while it remained stationary during the period that the 40 acid was eating the bottle.

The present invention has for its object to 45 provide a device and method of ascertaining whether or not a well hole has seriously deviated from the vertical while the drill pipe is in the well, thus eliminating the danger of hanging up or losing parts in the well. The drill pipe must be withdrawn from the well at fairly frequent intervals to replace the worn bit with a new bit,

and it is contemplated that the present device and method may be used just prior to the withdrawal of the drill pipe from the well for purposes of changing bits so that no additional labor is required over that necessary to pull out the 5 drill pipe for the purpose of changing bits.

The present invention also contemplates the provision of a suitable device wherein adequate precautions are taken to enable the go-devil to readily and quickly pass through the tool joints 10 of the drill pipe and to prevent breakage of the indicating and recording means.

Another object of the invention is to provide an acid bottle go-devil having a novel, advantageous and simple construction for mounting the 15 acid bottle in the body.

With the foregoing and other objects in view, which will be made manifest in the following detailed description, and specifically pointed out in the appended claims, reference is had to the 20 accompanying drawing for an illustrative embodiment of the invention, wherein:

Fig. 1 is a view in side elevation of the improved acid bottle go-devil.

Fig. 2 is a longitudinal vertical section through the same.

Fig. 3 is an enlarged partial vertical section through the acid bottle go-devil, illustrating in detail the manner in which the acid bottle is mounted within the body.

Fig. 4 is a horizontal section taken substantially upon the line 4—4 upon Fig. 3.

Fig. 5 is a horizontal section taken substantially upon line 5—5 upon Fig. 1.

Referring to the accompanying drawing, 35 wherein similar reference characters designate similar parts throughout, the improved acid bottle go-devil comprises a body having two rigid ends. The lower end 10 is preferably formed of metal and is pointed to facilitate its passing 40 through the openings through tool joints in a drill pipe. This pointed end is provided with a shank 11 presenting a serrated or shouldered exterior surface. This shank is embedded in the lower end of a long cylindrical section 12 of resilient live rubber. The upper end 13 is hollow 45 and is internally threaded, as indicated at 14.

It is provided on its lower end with a shank 15, which has a serrated or shouldered exterior surface embedded in the upper end of the long 50 cylindrical rubber connecting member 12. The rubber connecting member 12 enables the lower end 10 to be moved laterally with respect to the upper end 13 and does not prevent the ends from being moved out of alignment with each other. 55

It also forms a resilient or cushioning connection between the two ends. A threaded closure 16, having a squared boss 17, is adapted to be screwed into the top of the upper end 13. The closure 16 has a reduced lower end 18, which is threaded, to receive a metal container 19. Within the metal container, at the bottom thereof, there is positioned a pad 20 of soft resilient sponge rubber or the like, and suitable springs 21 are mounted 5 on the inside of the container 19 and bear against the sides of the acid bottle 22 disposed therein. The springs 21 keep the acid bottle 22 centrally of the container 19 to assist in preventing shocks from being transmitted thereto. The acid bottle 10 is closed by a rubber plug 23, which may be fastened to the reduced lower end 18 of the closure 16.

When it is desired to determine whether the bottom of a well hole is inclined or not, the improved acid bottle go-devil is assembled and acid 20 24, or other indicating means, is placed in the bottle 22. It will be readily understood by those familiar in the art that the correct quantity of acid is used of such strength that it will eat the 25 glass of the acid bottle 22 and form a marking thereon, which when the device is recovered will indicate the position in which the go-devil was disposed when it came to rest. The acid or other indicating material having been placed in the 30 bottle, the bottle is placed in the container and the closure 16 screwed into the container, after which the closure with the attached acid bottle and container are screwed into the shell provided by the upper end 13. The kelly on the drill 35 stem is removed and the go-devil is dropped or lowered through the drill pipe.

As it very seldom occurs that a deep well hole is absolutely straight, the go-devil during its fall will usually strike the sides of the drill pipe and 40 encounter shoulders afforded by tool joints. On encountering the shoulders, the rubber connecting member 12 allows the lower pointed end 10 to move laterally and pass through the tool joint without transmitting a severe shock either from 45 bending or compression of the rubber connecting member 12 to the acid bottle. By virtue of the fact that the body can bend, it will in effect worm its way through the openings in the tool joints while dropping and no severe shocks will be 50 transmitted to the bottle, breaking it.

When the go-devil reaches the bottom of the drill pipe it is kept in the drill pipe by the bit mounted on the bottom thereof. Where bits are provided with circulation ports opposite the center of the drill pipe, the pointed end 10 will enter the circulation port and the device will come to 55 rest. The action of the acid 24 on the bottle 22 is carefully timed and the device is allowed to rest at the bottom of the drill pipe a sufficient length 60 of time so that a good clear mark will be formed on the bottle, to give the desired indication. Thereafter the drill pipe is pulled out of the hole and the go-devil disassembled to obtain the indication recorded.

65 As clearly shown upon Figs. 1 and 2, the pointed lower end 10 is preferably provided on its exterior surface with long vertical grooves or passages 25. These grooves serve to permit circulation fluid to drain out of the drill pipe while the 70 drill pipe is being pulled out of the hole, in the event that the pointed end 10 on the go-devil enters the discharge port in the bit, consequently no "wet jobs" would ever be required in pulling the drill pipe after the improved go-devil has 75 been used.

Using the above-described method and apparatus it will be noted that the inclination recording structure is protected against becoming caught in the well by virtue of the fact that it is kept within the drill pipe while in the well hole. In this manner, if any caving of the well should take place, while the inclination is being determined and recorded, the inclination recording device will not become lost as long as the drill pipe itself is recoverable.

From the above described method and construction it will be appreciated that a novel, advantageous and simple, method and device is provided, which will give an indication as to the inclination of the bottom of a well hole and suitable and satisfactory precaution is provided for against breakage of the acid bottle.

Various changes may be made in the details of construction without departing from the spirit or scope of the invention as defined by the ap- 20 pended claims.

I claim:

1. A device of the class described comprising an elongated body adapted to be dropped or lowered into a well, said body having rigid ends, 25 means forming a flexible connection between the ends enabling one end to move laterally with respect to the other, and means associated with the body for indicating its inclination when the body comes to rest near the bottom of the well, said flexible connection also providing a resilient cushion between the ends of the body.

2. A device of the class described comprising an elongated body at least the major portion of which is formed of flexible resilient rubber, said body being adapted to be dropped or lowered into a well, and means on said body for indicating its inclination with respect to the vertical when the body comes to rest near the bottom of the well.

3. A device of the class described comprising a body having upper and lower rigid ends, the lower end being pointed, an elongated section of flexible rubber connecting said ends, said body being adapted to be dropped or lowered into a well, and means on the upper end of said body for indicating its inclination with respect to the vertical when the body comes to rest near the bottom of the well.

4. A device of the class described comprising a body adapted to be dropped or lowered into a well, said body providing a rigid shell, a closure for said shell, a container connected to the closure, an acid bottle disposed within said container, and resilient means disposed between the acid bottle and the container.

5. A device of the class described comprising an elongated resilient rubber body, there being a pointed end at the bottom of said body, a shell at the top of said body, a container disposed therein, an acid bottle disposed within said container, and resilient means disposed between the acid bottle and the container.

6. A device of the class described comprising an elongated resilient rubber body, there being a pointed end at the bottom of said body, a shell at the top of said body, a container disposed therein, an acid bottle disposed within said container, and resilient means disposed between the acid bottle and the container, the pointed end of the body having passages thereon as and for the purpose described.

7. The method of determining the inclination of a well hole adjacent the bottom thereof which comprises dropping freely through the drill pipe

in the well hole a cushion protected instrument adapted to form a record of the position of the instrument with respect to the vertical when it comes to rest, allowing the instrument to come to rest at the bottom of the drill pipe, withdrawing the drill pipe, and reading the record made.

8. The method of determining the inclination of a well hole adjacent the bottom thereof which comprises dropping freely through a drill pipe in the well a cushion protected container containing a liquid adapted to form a record of the position assumed by the surface of the liquid when the container comes to rest, allowing the container to come to rest at the bottom of the drill pipe and cause the record to be formed, withdrawing the drill pipe, and reading the record.

9. The method of determining the inclination of a well hole adjacent the bottom thereof which comprises dropping freely through a drill pipe in the well a cushion protected bottle containing acid which acid is adapted to etch the walls of the bottle on coming to rest, allowing the bottle to come to rest at the bottom of the drill pipe, withdrawing the drill pipe, and reading the record formed by the etched walls of the bottle.

10. Apparatus for determining the inclination of well holes comprising in combination a string of drill pipe disposed in said well hole, a free falling elongated holder having a container therein, the container having an etching liquid, said holder and container being adapted to drop by gravity through said string and means in said string to arrest the travel of and support said holder, said string being adapted to elevate the holder and container to the top of the well hole on hoisting the string.

11. A device for determining the inclination of a bore hole at a predetermined point therealong, comprising an elongated body adapted to be dropped into and to pass freely through a drill pipe positioned within said bore hole, the said body having provided therein a chamber or recess and a detachable closure therefor, an inclination recording instrument supported within said chamber, and resilient means disposed between said instrument and the chamber to cushion the instrument against shock incident to its falling through the drill pipe.

12. A device for determining the inclination of a bore hole at a predetermined point therealong, comprising an elongated body adapted to be dropped into and to pass freely through a drill pipe positioned within said bore hole, the said body having provided therein a chamber or recess and a detachable closure therefor, an acid bottle recording device supported within said chamber, and resilient means disposed between said bottle and the chamber to cushion the bottle against shock incident to its falling through the drill pipe.

13. The method of ascertaining whether a well being drilled by a rotary well drilling apparatus has deviated from the vertical which comprises dropping through the fluid in the drill pipe of such apparatus while the drill pipe is in the well an instrument capable of indicating its position with respect to the vertical, allowing the instrument to come to rest in the drill pipe and make the indication, and withdrawing the drill pipe from the well.

14. The method of ascertaining whether a well being drilled by a rotary well drilling apparatus has deviated from the vertical which comprises dropping through the fluid in the drill pipe of such apparatus while the drill pipe is in the well an

instrument capable of indicating its position with respect to the vertical, allowing the instrument to come to rest in the drill pipe and make the indication, withdrawing the drill pipe from the well, and in so doing allowing the fluid in the drill pipe to drain out around the instrument.

15. The method of ascertaining whether a well being drilled by a rotary well drilling apparatus has deviated from the vertical which comprises dropping through the fluid in the drill pipe of such apparatus while the drill pipe is in the well an instrument capable of indicating and recording its position with respect to the vertical, allowing the instrument to come to rest in the drill pipe and to indicate and record its position with respect to the vertical and consequently the approximate position of that portion of the drill pipe near the point where the instrument came to rest, withdrawing the drill pipe, recovering the instrument, and reading the record made.

16. The method of ascertaining whether a well being drilled by a rotary well drilling apparatus has deviated from the vertical which comprises dropping through the fluid in the drill pipe of such apparatus while the drill pipe is in the well an instrument capable of indicating and recording its position with respect to the vertical, allowing the instrument to come to rest in the drill pipe and to indicate and record its position with respect to the vertical and consequently the approximate position of that portion of the drill pipe near the point where the instrument came to rest, withdrawing the drill pipe, recovering the instrument, and reading the record made, and during the withdrawing of the drill pipe allowing the fluid therein to drain therefrom about the instrument.

17. An apparatus for determining the inclination of well holes comprising, in combination, an elongated body adapted to be dropped or lowered through the fluid in a drill pipe while the drill pipe is in a well, means mounted on the body for indicating and forming a record of the position assumed by the body after it has come to rest in the drill pipe.

18. An apparatus for determining the inclination of well holes comprising, in combination, an elongated body adapted to be dropped or lowered through the fluid in a drill pipe while the drill pipe is in a well, means mounted on the body for indicating and forming a record of the position assumed by the body after it has come to rest in the drill pipe, said body having passages thereon providing for the draining of the fluid from the drill pipe during the withdrawing of the drill pipe from the well to obtain the record formed.

19. The method of ascertaining whether a well being drilled by a rotary well drilling apparatus has deviated from the vertical which comprises introducing into the drill pipe of such apparatus while the drill pipe is in the well an instrument capable of indicating and recording its position with respect to the vertical, allowing the instrument to come to rest near the bottom of the drill pipe after descending therein and make the record so as to indicate the approximate inclination of the drill pipe near the point where the instrument comes to rest and consequently the approximate inclination of the well hole being drilled, recovering the instrument and reading the record made.

20. The method of ascertaining whether a well being drilled by a rotary well drilling apparatus has deviated from the vertical which comprises introducing into the drill pipe of such apparatus

5 while the drill pipe is in the well an instrument capable of passing downwardly through the drill pipe and indicating and recording its position with respect to the vertical, causing the instrument to come to rest in the drill pipe after descending therein and make the record so as to in-

dicate inclination of the drill pipe near the point where the instrument comes to rest and consequently the approximate inclination of the well hole thereabouts, recovering the instrument and reading the record made.

C. A. REINHARD. 5
